(71) Applicant: **Thor Tech, Inc.**, Elkhart, IN (US)

(72) Inventors: **Mark Bullock**, Elkhart, IN (US); **Jon Brock**, Warsaw, IN (US)

(73) Assignee: **Thor Tech, Inc.**, Elkhart, IN (US)

(**) Term: **15 Years**

(21) Appl. No.: **29/846,118**

(22) Filed: **Jul. 13, 2022**

CLAIM

The ornamental design for an electronic device with graphical user interface, as shown and described.

DESCRIPTION

The FIGURE is a front view of an electronic device with graphical user interface showing the claimed design. The outermost dashed lines in the figures show an electronic device that includes a display screen and form no part of the claimed design. The other dashed lines show portions of the graphical user interface that form no part of the claimed design.
